PRINTER'S CHASE LOCKING DEVICE

Filed March 31, 1930

UNITED STATES PATENT OFFICE

JAMES EDGAR LEE, FREEMAN BARNEY, AND PHILIP J. BEATTY, OF GRAND HAVEN, MICHIGAN, ASSIGNORS TO THE CHALLENGE MACHINERY COMPANY, OF GRAND HAVEN, MICHIGAN, A CORPORATION OF MICHIGAN

PRINTER'S CHASE-LOCKING DEVICE

Application filed March 31, 1930. Serial No. 440,451.

This invention relates to a printer's chase locking device which is of utility in making a very rapid locking of set-ups of type or the like in a chase. Usually the set-ups are of

metal bottom preferably the constructive details of the chase form no part of and import no limitation upon the present invention.

5 substantially uniform size and a number of them, usually four, may be located in the chase and by a single operation all four of the set-ups securely locked in place by a single manual operation. The invention is particularly useful in connection with printing the pages of directories, such as telephone directories, though in no sense limited thereto as books of any size similar to that of directories may have set-ups for the pages thereof, and

55 substantially midway between the ends of the chase and extending across the same are dividing bars 3 the adjacent ends of which are spaced apart and are connected together by an overlying metal plate 4 through which a circular opening is made. At each corner 60 of the chase filler blocks 5 are located extending toward each other from the sides of the chase, at their inner end portions being reduced in thickness as indicated at 5a, the adjacent ends of the parts 5a being parallel to 65 each other and serving as guides for parts of the locking mechanism as will hereafter appear. A flat metal bar 6 is secured at the upper sides of and inner edges of the blocks 5, extending beyond said inner edges and 70 having a length equal substantially to the distance between the sides 1 of the chase as fully shown at the upper part of Fig. 1.

10 It is an object and purpose of the present invention to provide a chase locking apparatus of the type noted whereby rapid change of set-ups in a chase and locking of the new set-ups in place is attained. For instance, in printing a telephone directory, a chase carrying and having locked therein the type set-ups for four of the pages may be used in 15 printing until the entire run of such pages of the directory is completed, whereupon the set-ups for four other pages may be put in the chase, the first four being quickly released and removed and the others substituted and almost instantly locking in the chase, thereby saving a great deal of time with a consequent economy in printing. Many other objects and purposes subsidiary to the primary object stated will be apparent

75 to the following description taken in connection with the accompanying drawing, in which, the type set-ups, which are inked to give the impressions to paper in printing, are of 75 rectangular form as indicated at 7. The ends of the set-ups 7 bear against bars 8 and 9, the bars 8 coming against the cross bars 3 previously described, while the inner side edges of the set-ups 7 bear against other flat 80 bars 10 located lengthwise of the chase parallel to each other but spaced a distance apart.

20 The bars 9 at the outer ends of the set-ups 7 come against bars 11, as shown in Fig. 1, which at their outer edges are formed with 85 spaced apart inclines 12; and the inner side bars 10 bear against somewhat similar bars 13 having flat sides against which the bars 10 seat and at their inner sides being formed with a plurality of spaced apart inclines 14 90

as shown. The bars 13, having the inclines 14, are likewise a distance apart from each other and between each of the pairs of bars 13, one pair above and the other pair below the cross members 3, a locking bar 15 is 95 mounted which is provided with complementary spaced inclines to bear against the inclines 14 on the bars 13 whereby, on movement of the bars 15 lengthwise toward each other, the bars 13 are wedged apart and 100

25 Fig. 1 is a plan view of a chase having a plurality of page set-ups locked therein using my invention, and

30 Fig. 2 is a fragmentary enlarged plan illustrating the manner in which the locking mechanism is operated.

35 Like reference characters refer to like parts in the different figures of the drawing.

The printer's chase may be made of any suitable material and is of rectangular form having parallel sides 1 spaced from each other and parallel spaced ends 2. While in 40 practice the chase is provided with a sheet

thereby force the set-ups 7 toward the sides 1 of the chase and into very firm engagement therewith.

The outer ends of the bars 15 are provided with extensions 16 to each of which a head 17 is permanently secured. The heads 17 are located between the ends of the parts 5a previously described which serve as guides for the heads in their movements. Levers 18 are attached to each of the heads 17, one at each side thereof, and extend outwardly therefrom and at an angle to the ends of the chase having pivotal connections at their outer ends to bars 19. The bars 19 at their 15 outer sides have a flat sliding engagement against the inner sides of the blocks 5 and at their inner sides are formed with spaced inclines 20 to cooperate with the like inclines 12 on the bars 11, previously described, and thereby wedge the bars 11 inwardly and force the set-ups 7 into secure locking engagement 20 against the bars 8.

In order that the movement of the various bars 15 and 19 shall occur simultaneously and in like amounts the inner end of each bar 15 has an operating member 21 adjustably connected thereto threading onto the threaded inner end 21 of a bar 15. The operating members 22 pass by each other and at 30 their adjacent sides are provided each with a series of rack teeth 23 which pass underneath the opening in the plate 4. A key 24 having a pinion like head is adapted to be passed through the opening in the plate 4 and engage with the teeth of both racks 23 whereby, on turning the key in one direction, the two bars 15 may be drawn simultaneously lengthwise toward each other producing a simultaneous outward movement to all of the 35 bars 19 and the locking movement of all the locking bars 15 and 19 occurs simultaneously; and evidently on turning the key in the opposite direction the release of the locking appliance is instantly effected. The plates 6 40 serve as guides and holders over the locking bars 19 and also pass over the links and the ends 16 of the bars 15, keeping them from disengagement from the chase.

Although the locking device has been 50 shown and described as used with a printer's chase it is conceived that it may be used equally well with a printer's galley and it is intended that the word "chase" wherever used in the claims shall be considered as of 55 sufficient scope to include a galley or any other analogous frame or receiver of a type set-up.

The construction is very practical and has so proved in use. With the release of type 60 set-ups, a plurality of them in a chase, and the replacement thereof by others with substantially instant locking of the same in the chase is very effectively accomplished. The invention is defined in the appended claims 65 and is to be considered comprehensive of all

forms of structure coming within their scope.

We claim:

1. In combination, a printer's chase, a plurality of set-ups located in the chase, and manually operable means engaging against said set-ups whereby all of the same may be simultaneously locked in the chase or released therefrom. 70

2. In combination, a printer's chase, a plurality of set-ups located in said chase, locking means to engage against one end and one side of each of said set-ups to force the opposite ends and opposite sides of said set-ups against the chase, and a single manually operable means for engaging said locking means to 80 operate the same thereby simultaneously locking the set-ups in said chase. 75

3. In combination, a printer's chase of rectangular form, a plurality of set-ups located in said chase and spaced from each other, one side and one end of each of said set-ups bearing against relative rigid and stationary parts of the chase, and manually operable means located between said set-ups and against the opposite ends thereof for simultaneously bringing locking pressure against an opposed side and end of each set-up to force the same into locking engagement against said stationary parts of the chase. 85 90

4. In combination, a rectangular printer's chase, a plurality of set-ups of rectangular form located in the chase, one end and one side of each of said set-ups bearing against relatively rigid and stationary parts of the chase, the opposite sides of said set-ups being spaced 100 from each other and the opposite ends thereof being spaced from the ends of the chase, locking means located between said opposite sides of said set-ups and against said opposite ends thereof arranged and connected for simultaneous operation, and a single manually operable means for operating said locking means to force all of the set-ups simultaneously, at said first mentioned sides and ends, against the said stationary parts of said chase. 105

5. In combination, a printer's chase of rectangular form, a printer's set-up of rectangular form located in said chase with one side and one end thereof bearing against relatively rigid and stationary parts of the chase, a 115 movable locking bar located along the opposite side of the set-up, a second movable locking bar located at the opposite end of said set-up, connections between said locking bars for moving the same simultaneously, and means for manually operating one of said locking bars to thereby simultaneously cause the operation of the other locking bar and force said set-up at its first mentioned side and end against said stationary and rigid parts of the chase. 120

6. A printer's chase of rectangular form having parallel sides and parallel ends, guide blocks located one at each corner of the chase and parallel to the ends thereof, stationary 125

abutments located transversely of the chase between the ends thereof and parallel to said ends, four printer's set-ups located in said chase each having an end bearing against said 5 abutments and a side bearing against a side of the chase, said set-ups being spaced apart at their opposite sides and spaced at their opposite ends from said guide blocks, a locking bar slidably mounted against and at the 10 inner side of each of said guide blocks, a locking bar located lengthwise between said opposite sides of the set-ups at each side of said abutments, connections between the outer ends of said last mentioned locking bars and the 15 first locking bars, all of said locking bars having wedge surfaces, and bars having cooperating wedge surfaces located between said locking bars and the adjacent sides and ends of said set-ups combined with means located substantially at the center of the chase for simultaneously moving the last mentioned locking bars between the sides of the set-ups simultaneously and in opposite directions.

7. A construction containing the elements 25 in combination defined in claim 6, wherein the connecting means between the outer ends of the second mentioned locking bars and the first mentioned locking bars each comprises a head secured to the outer end of each of the 30 second mentioned locking bars and links pivotally attached one at each side of each head and extending to and pivotally connected with the first mentioned locking bars, said heads being located and guided between 35 the inner ends of said blocks.

8. In combination, a printer's chase having a side and a transversely extending end, a type set-up located in said chase, and a locking device comprising a wedge bar located at 40 a side and an end of said type set-up, a toggle lever connected to both of said wedge bars whereby longitudinal movement of one causes similar longitudinal movement of the other and a single means to actuate one of said 45 wedge bars.

9. In combination, a printer's chase having a side and a transversely extending end, a type set-up located in said chase, and a locking device comprising two wedge bars located at 50 a side and an end of said type set-up, respectively, a single means to actuate one of said wedge bars and a toggle lever connected to the other of said wedge bars and actuated by movement of said single actuating means, 55 whereby said single actuating means effects longitudinal movement of both wedge bars.

In testimony whereof we affix our signatures.
